FIG. 1 is a front perspective view of a combination bird bath and feeder showing my new design;

FIG. 2 is a rear elevational view thereof;

FIG. 3 is a side perspective view thereof; and

FIG. 4 is a top plan view thereof.

The side of the combination bird bath and feeder opposite that shown in FIG. 3 is substantially a mirror image of the side shown in FIG. 3.

I claim:

The ornamental design for a combination bird bath and feeder, substantially as shown and described.
